2,268,892

AUTOMOBILE DOOR LOCK

Algott L. Nelson, Detroit, Mich., assignor to Ternstedt Manufacturing Company, Detroit, Mich., a corporation of Michigan

Application February 2, 1940, Serial No. 316,916

10 Claims. (Cl. 292—164)

This invention relates to an automobile door lock.

From the standpoint of safety it has become desirable to eliminate the projecting outside door handle which is turned or rotated to retract the latch bolt. Instead of this projecting outside door handle it has been proposed to substitute therefor a so-called flush outside door handle or a curved handle fixed at each end to the door with a push button control for the latch bolt. With either type of latch bolt control it is desirable to have a latch bolt that can be retracted easily.

It is an object of this invention to produce a door latch provided with a bolt which can be retracted easily and with a minimum expenditure of power. This object is achieved by providing a latch bolt with means for storing energy as the door is swung open which is arranged to expend this energy in the retraction of the bolt preparatory to opening the door.

This invention also contemplates storing energy otherwise wasted in the opening of the door for facilitating retraction of the latch bolt preparatory to opening the door. This object is achieved by combining the door check with energy storing means which is energized as the door check checks the door and deenergized in retracting the latch bolt preparatory to opening the door.

It is also an object of this invention to produce an automobile door lock which is admirably suited for use with a door having a narrow or thin lock pillar.

In the drawings:

Fig. 1 is an inside fragmentary view of an automobile vehicle door hinged at its forward edge showing the combined latch and door check.

Fig. 2 is a section along the line 2—2 of Fig. 1.

Fig. 3 is an enlarged detail of the lock and door check as viewed from without the automotive vehicle.

Fig. 4 is a section along the line 4—4 of Fig. 3.

Fig. 5 is a section along the line 5—5 of Fig. 3.

Fig. 6 is a view similar to Fig. 3 showing the toggle broken and the bolt retracted while the door is yet closed.

Fig. 7 is a section along the line 7—7 of Fig. 1.

Fig. 8 is a view similar to Fig. 6 showing the position of the locked parts with the door swung partially open.

Fig. 9 is a view similar to Fig. 8 but showing the door fully opened.

Referring more particularly to the drawings there is shown a portion 1 of an automobile body having a door 2 hinged at its forward edge 3. The body pillar 4 is provided with a striker 5

arranged to interengage a bolt 6 projected by a convolute spring 7.

The bolt 6 is arranged to be retracted by an energy storing mechanism in the form of a convolute spring 8 and a lever 9 connected to the bolt by draft link 10. One end of the draft link is pivotally connected to the lever 9 as at 46 and the other end of the link is connected to the bolt 6 with a lost motion connection in the form of a pin 12 which engages the link 10 in the elongated slot 13. The spring 8 is fixed at one end to the post 14 and the other end is fastened to the lever 9 by a lug 15 struck out of the lever 9 and turned over the end of the spring 8. The post 14 is fixed on the support plate 16 and the lever 9 is pivoted on the post 14. The plate 16 is secured to the inner door panel 25 by bolts 26.

It is proposed to utilize the energy of the door as it swings outwardly to energize the spring 8. To this end the door is provided with a door check in the form of a check link 17 which passes through a suitable opening therefor in the door pillar 18 and is hinged to the body pillar 19 as at 20. The check link 17 is provided with a rubber stop 21. The inner end of check link 17 is connected to a bracket 23 which is fixed to a draft bar 22 which is slidably supported on the support plate 16. For slidably mounting the draft bar 22 on the plate 16, the plate is provided with elongated slots 27 and 28 having their longitudinal edges flanged outwardly from plate 16. The draft bar 22 is retained by the flanged edges as illustrated. The draft bar 22 is provided with pressed in portions 29 which engage the flanged edges of slots 27 and 28 to guide motion of draft bar 22. A plate 30 is secured to the back of the portions 29. The plates 22 and 30 overlap the plate 16 on each side of the slots 27 and 28 as at 31. The draft plate 22 is connected to lever 9 through a toggle consisting of links 32 and 33.

The plate 22 has fixed thereto a pin 34 which pivotally supports toggle link 32 in elongated slot 35. The link 32 is pivotally connected to link 33 by pin 36. Link 33 is pivotally supported on lever 9 by pin 37. A coil spring 38 is mounted upon pin 37. One end 39 of the coil spring engages a lug 40 struck out of link 33 and biases the toggle toward over center position as shown in Fig. 3. The other end 41 of the spring engages lug 42 turned up from lever 9.

From the above it is evident that as the door is swung open the pull on draft bar 22 is transmitted through toggle links 32 and 33 to lever 9 which winds up or compresses spring 8. Thus when the door is swung closed, spring 8 must be

55

prevented from unwinding until the energy stored therein is to be utilized. To this end a toggle lever is provided in the form of toggle links 44 and 45. Link 45 is pivotally connected to lever 9 as at 46 and link 44 has an elongated slot 50 which has a lost motion pivotal engagement with pin 51 fixed on plate 16. Coil spring 47, mounted on pin 51, biases the toggle to made or over center position, shown in Fig. 3. The toggle links 44 and 45 are pivotally connected by pin 52. Link 45 is provided with stop 53 which abuts the top edge of link 44 when the toggle is in over center position, Fig. 3.

For breaking the toggle from the outside of the door there is provided a handle 54 pivotally mounted as at 55 and connected by link 56 with arm 57. Link 56 has a lost motion connection with arm 57 in the form of a pin 58 fixed to arm 57 which engages link 56 in the elongated slot 59. Arm 57 is stamped integrally with toggle arm 44. Handle 54 is flush with the outside belt molding 60. When handle 54 is swung outwardly to dotted line position, Fig. 2, draft link 56 acts through arm 57 to break toggle 44, 45 which permits spring 8 to rotate clockwise, Fig. 3, and retract the bolt 6.

The toggle 44, 45 can be broken from within the body by means of slide member 24 slidably mounted on the plate 16. The plate 16 is provided with a pin 61 which engages lug 62, Fig. 4, on toggle 45 when the slide 24 is raised to break the toggle 44, 45. To prevent raising of the slide 24 when the door is open, the slide is provided at its lower end with pin 63. Slide 22 is provided with a notch 64 which is aligned with pin 63 only when the door is closed, Fig. 6, and which receives the pin 63 when the slide 24 is raised. When the door is opened, notch 64 is offset from pin 63 so that pin 63 is beneath the lower edge 65 of slide 22 which prevents raising of slide 24.

The operation of the latch is as follows: When the door is closed and the bolt interengaged with the striker, the position of the parts is shown in Fig. 3. At this time both toggle levers are made and coil spring 8 is under compression. To retract the bolt the toggle 44, 45 is broken upwardly either by swinging the outside door handle 54 outwardly or by raising the slide 24 from within the body by means of lever 66. As pivot 52 swings above center, that is, a line passing through pivots 46 and 51, lever 9 is released so that spring 8 can now unwind or utilize its energy to retract the bolt. As spring 8 unwinds, lever 9 moves clockwise, Fig. 3, thus pulling draft link 10 to the right, Fig. 3, or to the left, Figs. 1 and 2, retracting bolt 6 thereby permitting the door to open. Clockwise rotation of the lever 9 is stopped when pin 34 reaches the right hand end of slot 35, Fig. 6. The length of slot 35 is sufficient to permit full retraction of bolt 6 out of interengagement with striker 5.

Since it is proposed to utilize the opening movement of the door to reenergize or reload spring 8, this is achieved as follows: As the door opens, check link 17 draws slide 22 to the right, Fig. 6, thereby causing cam edge 67, acting through pin 68, to lower slide 24. The force exerted by slide 22 is transmitted through toggle 32, 33, pin 37 to lever 9, rotating it counterclockwise and again compressing spring 8. As lever 9 rotates counterclockwise, Fig. 6, toggle 44, 45 is again made and is returned to over center position by spring 47. This action takes place during the initial portion of the door movement as it is swung open. Fur-

ther opening movement of the door causes the overhanging end 68 of toggle link 33 to engage lug 42 turned outwardly from lever 9, Fig. 8, thus causing the toggle to break and swing to the position illustrated in Fig. 9. A pin 70 fixed on plate 16 above the end 68 of the toggle is added as a precautionary measure to act as a stop for breaking the toggle in case lug 42 has not broken the toggle by the time end 68 engages stop 70. As the toggle 32, 33 breaks over center, lever 9 is rotated slightly counterclockwise, Fig. 8. Since toggle 44, 45 is already made or over center, it too must move to the left, Fig. 8. This is permitted by the lost motion connection between the elongated slot 50 and pin 51. The door now swings fully open until arrested by block 21 on the check link 17 abutting the pillar 18. The position of toggle 32, 33 at this time is shown in Fig. 9.

As the door swings closed, toggle 32, 33 is again straightened by the return movement of the slide 22 acting through pin 34 and spring 38 throws the toggle to over center position, Fig. 3. As the bolt 6 rides up the striker 5, link 10 remains stationary because pin 12 is free to slide backward in elongated slot 13.

It should be noted from the above description that this door lock is well adapted for an automobile door having a thin or narrow pillar 100. As shown, the door is provided with a sliding panel 101 and a pivoted panel 102, as shown in the Fisher Patent No. 2,048,605. Since the entire latch mechanism, including the bolt 6 and the retracting motor in the form of spring 8, is positioned in the window well on the inside of the sliding panel 101, the power for retracting the bolt is not derived from the outside of the door. Therefore it is only necessary to have a control mechanism for the energy storing means 8 on the outside of the door in the form of handle 54 and its connection with the toggle 44, 45. Thus the power means for retracting the bolt does not cut across the plane of the sliding panel 101 and only sufficient power has to be transmitted about the window 101 to break the toggle 44, 45. Since the power required to break the toggle is considerably less than that required to retract the bolt, therefore a very thin transmission member can be used for this purpose.

I claim:

1. In a door hinged to a support and arranged to be opened and closed and having a latch including a retractable bolt mounted on the door, the combination with said latch of energy storing means mounted on the door, a draft connection between the energy storing means and the stationary door support for energizing the energy storing means as the door is opened, a draft connection between the energy storing means and the retractable bolt, a manual control for the energy storing means manually operable to release the energy in said energy storing means whereby the stored energy is utilized to retract said bolt, and means operable when the door is opened to render the manual control ineffective to release the energy in said energy storing means.

2. In an automotive vehicle body having a door opening wherein a door is hinged to the body at an edge of said opening and a check is provided for limiting the opening of said door and a retractable bolt is carried by the door, the combination with said check and said bolt of resilient energy storing means, connections between the energy storing means and the bolt, a

connection between the energy storing means and the door check whereby the resilient energy storing means is energized by the check as the door is opened, a manual control for the energy storing means, and means for rendering the manual control ineffective when the door is opened whereby the manual control can be operated only when the door is closed to release the energy in said energy storing means for retracting the bolt.

3. In an automobile body having a door opening wherein a door is hinged to the body at an edge of said opening and provided with a retractable latch bolt, the combination with said latch bolt of a lever, a draft connection between the lever and the latch bolt, draft connections between the edge of said door opening and the said lever for rotating the lever as the door is opened, resilient means connected to said lever and placed under stress when the lever is rotated in the opening of the door, a toggle connected to said lever for retaining the lever in position to stress said resilient means, a manually operated control for breaking said toggle to release said lever whereby the energy stored in said resilient means rotates the lever in reverse direction to retract the bolt, the said toggle being returned to made position by rotation of the lever during the opening of the door.

4. In an automobile body having a door opening wherein a door is hinged to the body at an edge of said opening and a retractable latch bolt is provided on said door, the combination with said latch bolt of a lever, a draft connection between the lever and latch bolt, a draft link connected to the edge of the door opening, a first toggle connecting the said lever and the draft link, the said draft link and first toggle rotating the lever as the door is opened, resilient means connected to said lever and placed under stress when the lever is rotated in the opening of the door, a second toggle connected to said lever for retaining the lever in position to stress said resilient means, a manually operated control for breaking said second toggle to release said lever whereby the energy stored in said resilient means rotates the lever in reverse direction to retract the bolt, the said second toggle being returned to made position by rotation of the lever during the opening of the door.

5. In an automobile body having a door opening wherein a door is hinged to the body at an edge of said opening and a retractable latch bolt is provided on said door, the combination with said latch bolt of a lever, a draft connection between the lever and the latch bolt, draft connections between the edge of said door opening and the said lever for rotating the lever as the door is opened, resilient means connected to said lever and placed under stress when the lever is rotated in the opening of the door, a toggle connected to said lever for retaining the lever in position to stress said resilient means, a manually operated control for breaking said toggle to release said lever whereby the energy stored in said resilient means rotates the lever in reverse direction to retract the bolt, the said toggle being returned to made position by rotation of the lever during the opening of the door, and means connected to said manual control for rendering the same ineffective to break the toggle when the door is opened.

6. In an automobile body having a door opening wherein a door is hinged to the body at an edge of said opening and a retractable latch bolt

is provided on said door, the combination with said latch bolt of a lever, a draft connection between the lever and latch bolt, a draft link connected to the edge of the door opening, a first toggle connecting the said lever and the draft link, the said draft link and first toggle rotating the lever as the door is opened, resilient means connected to said lever and placed under stress when the lever is rotated in the opening of the door, a second toggle connected to said lever for retaining the lever in position to stress said resilient means, a manually operated control for breaking said second toggle to release said lever whereby the energy stored in said resilient means rotates the lever in reverse direction to retract the bolt, the said second toggle being returned to made position by rotation of the lever during the opening of the door, and means for breaking the first toggle after the second toggle has returned to made position whereby further opening of the door is ineffective to rotate said lever.

7. In an automobile body having a door opening wherein a door is hinged to the body at an edge of said opening and a retractable latch bolt is provided on said door, the combination with said latch bolt of a support plate, a lever rotatably mounted on the support plate, a draft connection between the lever and the latch bolt, a draft link having one end connected to the edge of the door opening, a toggle connecting the other end of the draft connection with the said lever for rotating the lever as the door is opened, a spring connected to the lever and placed under stress when the lever is rotated in the opening of the door, a second toggle having one end connected to the lever and a lost motion connection between the other end of the second toggle and the support plate, the said second toggle serving to retain the lever in position to stress said spring and breakable to release said lever whereby the energy stored in said spring rotates the lever in reverse direction to retract the bolt, and means actuatable during the opening of the door to break the first toggle after the lever has been rotated to stress the spring and the second toggle is returned to made position to hold the lever in spring stressing position.

8. In an automobile body having a body pillar and a door hinged to the body pillar and a retractable latch bolt in said door, the combination with said latch bolt of a support plate, a lever pivoted between its ends on the support plate, a draft connection between one end of the lever and the latch bolt, a draft link pivotally connected to the body pillar, a toggle pivotally connected at one end to said lever and a lost motion connection between the other end of the toggle and the draft link whereby when the toggle is made opening of the door acts through the draft link and toggle to rotate the lever in one direction, a spring stressed by the rotation of the said lever, a second toggle having one end connected to the lever and the other end connected to the support plate for releasably locking the lever in spring stressing position when the second toggle is made, manually controlled means for breaking the second toggle whereby the spring rotates the lever and retracts the bolt permitting the door to be swung open, a stop against which the first toggle abuts in the opening of the door after the second toggle is made to break the first toggle whereby further opening of the door is ineffective to rotate said lever.

9. In an automobile having a door swingably

mounted on a support and having a window well in said door and a window panel arranged to retreat into said well and a latch including a retractable latch bolt mounted in the well on the inside of the window, the combination with said latch of mechanical power means in the window well on the inside of the window panel for retracting the latch bolt, connections between said mechanical power means and the door support for energizing the power means during the opening of the door, and a manual control on the outside of the door for said power means including a connection passing about an edge of the window panel actuatable to release the energy in said power means for retracting the latch bolt. 15

10. In an automobile having a support and a door swingably mounted on said support with a window well in said door and a window panel

arranged to retreat into said well and a latch including a retractable latch bolt mounted in the well on the inside of the window panel, the combination with said latch of mechanical energy storing means in the window well on the inside of the window panel, unobstructed connections between the energy storing means and the door support for energizing the said means during the opening of the door, a toggle for maintaining the energy storing means energized, a manual control on the outside of the door including a connection passing about an edge of the window panel for direct connection of the control to said toggle whereby operation of the manual control breaks the toggle and deenergizes the energy storing means for retracting the bolt.

ALGOTT L. NELSON.
